GAS DISCHARGE TUBE

James D. Cobine, Schenectady, N. Y., assignor to
the United States of America as represented
by the Secretary of War

Application December 10, 1945, Serial No. 634,090

5 Claims. (Cl. 315—236)

1

This invention relates generally to electrical apparatus and more particularly to a random pulse generator utilizing a gas discharge tube and a magnetic field.

While it is generally appreciated that a gas discharge tube may be utilized as a random noise generator and as a pulse generator, it is not common knowledge that a gas discharge tube may be used to provide a random noise voltage, reinforced by random noise pulses, by the application of a magnetic field to the gas discharge occurring within such a tube.

It is an object of this invention to provide a noise generator whose output consists of random noise voltages and random pulses. Such an output voltage is accomplished by utilizing a conventional sweep circuit including a gas discharge tube and a resistor and capacitor combination with the gas discharge tube subjected to the influence of a magnetic field.

A random noise voltage and random pulse generator are useful for many purposes, one of which is to test the response of a receiver to noise.

Other objects, features, and advantages of this invention will suggest themselves to those skilled in the art and will become apparent from the following description of the invention taken in connection with the accompanying drawings in which:

Fig. 1 is a schematic diagram of a circuit utilizing the principles of this invention;

Fig. 2 is an elevation showing an assembly incorporating a gas discharge tube and two electromagnets; and

Fig. 3 is a graph showing the relationship of time versus output voltage, condenser current, and tube current of the circuit shown in Fig. 1.

Referring now to Fig. 1, a gas discharge tube 10 is shunted by a capacitor 11, and across the combination a source of direct-current potential is applied through a resistor 12.

Fig. 2 shows a physical arrangement of gas discharge tube 10 centered between two electromagnets 13, 13. Concerning the physical arrangement of the magnetic field with respect to the tube, it should be noted that the magnetic field is transverse to the longitudinal axis of the tube, which, it will be understood, is such as to effect a deflection of the electron flow.

Fig. 3 is a graph showing the probable process by which the random relaxation pulses are developed and strategic points on the graph have been designated by the letters A, B, and C, respectively, to promote clarity in the following discussion of the operation of this invention.

2

A gas discharge tube such as a type 6D4, connected in a circuit as shown in Fig. 1, is arranged at the center of a gap between two magnet pole faces as shown in Fig. 2, with the magnetic field transverse to the longitudinal axis of the tube. Such a device having the values of capacitor 11, plate resistor 12, the applied direct-current potential B+, and the flux density of the transverse magnetic field, all properly adjusted, will operate in such a fashion that the output pulses consist of noise reinforced by random pulses. The voltage output of this random pulse generator system will be substantially constant over a band of frequencies from 15 25 cycles per second to at least 100 kc.

A typical circuit such as illustrated in Fig. 1 might use a value of capacitance of 0.004 mfd., a resistance of 48,000 ohms, and a source of direct current 14, applied to the two electromagnets 13, 13 of Fig. 1, to produce a magnetic field of approximately 370 gauss.

The curves shown in Fig. 3 show the probable process by which the random relaxation pulses are developed. The capacitor 11 causes sufficient instability at the instant of a random positive noise pulse, at a time corresponding to point A, when the current is transferred from the arc in tube 10 to the capacitor 11, to cause extinction of the arc in tube 10. At the extinction of 25 the arc, corresponding to time B, the voltage across capacitor 11 increases during the time interval B—C as required by the applied voltage B+ and the R—C time constant of capacitor 11 and resistor 12.

35 The effect of the magnetic field is to delay the re-ignition of the arc in tube 10 until a relatively high voltage is again developed across capacitor 11 which then discharges to the arc voltage and conditions remain normal until another high positive noise pulse appears.

40 While there has been here described what is at present considered to be the preferred embodiment of the invention, it will be obvious to those skilled in the art that various changes and modifications may be made therein without departing from the scope of the invention.

45 What is claimed is:

1. A noise generator, comprising a normally conducting gas discharge tube having an anode and a cathode, a source of positive potential, and resistance means electrically connecting said anode to said source of potential, capacitor means electrically connecting said anode to said cathode and means for applying a constant magnetic field transverse to the longitudinal axis of said tube whereby the output of said tube con-

sists substantially of random noise and random pulses.

2. A random pulse and noise signal generator comprising a normally conducting electron tube relaxation oscillator circuit which is in a non-oscillatory state, said electron tube having an electron current flow path therein, and a source for a constant magnetic field positioned with respect to said tube for said field to deflect said electron current flow path.

3. A random pulse and noise signal generator, comprising a saw-tooth pulse oscillator circuit including a gaseous discharge device shunted by a storage condenser, being in a normal state of conductivity and having irregularly occurring periods of non-conductivity, said device having a space current flow path therein, and means for effecting a delay in the reestablishment of conductivity of said device, including a source for a constant magnetic field positioned for at least one component of said field to effect a deflection of said electron current flow path.

4. A pulsing system, comprising a gaseous electron discharge device having a space current path therein, a resistance in series with said device for connection therewith across a source of direct potential, said device being normally conductive, a storage condenser in shunt with said device, and a continually operative electromagnet having its pole faces positioned to pro- 30

vide a constant magnetic field having at least one component transverse to said space current path.

5. A noise generator comprising a gaseous electron discharge device having a space current path therein, a resistance in series with said device for connection therewith across a source of direct potential, said device being normally conductive, a storage condenser in shunt with said device, and a continually operative electromagnet having its pole faces positioned to provide a constant magnetic field acting to deflect the flow of space current, said normally conductive device being intermittently rendered non-conductive due to random noise pulses of an amplitude greater than a given amplitude, whereby a charging of said condenser occurs, said magnetic field acting to delay the reestablishment of the state of conductivity of said device.

JAMES D. COBINE.
